UNITED STATES PATENT OFFICE.

YOUNG STOKES ELLINGSWORTH, OF GENESEO, ILLINOIS.

HAND-TRIP FOR GRAIN-BINDERS.

1,307,246.

Specification of Letters Patent. Patented June 17, 1919.

Application filed September 21, 1918. Serial No. 255,119.

To all whom it may concern:

Be it known that I, YOUNG STOKES ELLINGSWORTH, a citizen of the United States, and a resident of Geneseo, in the county of 5 Henry and State of Illinois, have invented a new and useful Improvement in Hand-Trips for Grain-Binders, of which the following is a specification.

My invention relates to grain binders and 10 more particularly to binders of the type wherein an automatic tripping device is used, and has for an object to produce a hand tripping device operable independent of the automatic tripping mechanism, and 15 one to be used in heavy grain or where the grain is down and clogs the machine.

With the above and other objects in view my invention consists in certain novel features of construction, arrangement and combination of parts, as will be hereinafter described and pointed out in the claims, reference being had to the accompanying drawings, in which

Figure 1 is a perspective view of a portion 25 of the usual deck of a grain binder and accessory parts with my improvements applied,

Fig. 2 is a perspective view of the device 30 detached and the attaching elements.

My improvements which are applicable to 35 any such grain binders as the Deering, Deere and McCormick, comprises a rod lever 10 of sufficient length to reach over the top of the binder designated generally at 11 to the driver's seat (not shown), said rod lever 40 having at its free end a handle or crank 12 within easy reach of the driver.

Passing diagonally across the deck of the binder this rod passes through a guide loop, 45 said loop comprising an elongated eye 13 at the upper end of a plate 14 clamped to the brace rod 15 of the binder. The end of rod 10 opposite the handle end is bent at 16 and provided with an eye 17 which is fitted on 50 the finger or arm 18 at the upper end of a trip rod or bar 19 on which it is suitably held. The rod 19 then passes downwardly through a brace guide 20 having two or more openings 21 for adjustment, said brace guide 55 being bolted to the binder structure. Continuing downwardly the rod or bar 19 passes through a bracket 22 consisting of a perforate ear 23 angularly extending from a strap 24 having an enlarged loop 25 which is bolted to the part 26 of the binder. A coiled 60 spring 27 encircles the trip rod 19 below the

bracket 22 and bears at its upper end against the ear 23 and at its lower end against restraining pin or collar 28. Rod 19 then extends downwardly and terminates in a bend 60 or hook 29 which normally extends below and beneath the standard trip 30 used in this type of machines.

The device is shown in its normal or inactive position in Figs. 1 and 2 in full lines, 65 and in the dotted lines in Fig. 2 indicate the movements of the parts in functioning.

It should be noted that the device is a hand tripper, to be used in handling heavy 70 grain, or where the grain is down and clogging the machine. When this situation arises, the driver of the binder pushes the lever 10 at his side and this movement causes an upward pull on the trip rod 19 against the tension of the spring and lifts the automatic tripper 30 out of operative position, 75 whereupon the grain is tied and a bundle passes, so that the tier is ready for the grain which is piling up too fast.

As before stated, the improvements hereinafter set forth can be applied to any of the standard machines, and without the slightest changes in such machines, or without interfering with the normal functions of such machines. Nor is it necessary to make 80 any changes in the machines referred to.

Furthermore, the device is very easily handled and responds to very slight efforts on the part of the driver, as about one and one-half (1½) pounds of pressure is necessary to trip the tier.

I claim:

1. In a device as herein characterized, in combination, a grain binder including a trip dog, a hand lever extending over the deck of the binder and movably fulcrumed thereon, a tripping rod flexibly connected with said lever and angularly disposed relatively thereto, spring means engaging said rod for normally holding said rod in inactive position, and means carried by said rod for engaging said trip dog upon pivotal movement of the hand lever.

2. In a device as herein characterized, in combination, a hand lever adapted to extend over the deck of a grain binder, a crank handle at one end of said lever and an eye at its opposite end, a guide loop constituting a fulcrum for said lever intermediate its ends, a trip rod having an angular connection 105 with said eye, a guide brace engaging said tripping rod, a bracket mounted on the 110

binder and through which said tripping rod passes, a coiled spring surrounding said rod and engaging said bracket and said rod to normally depress the tripping rod, the lower end of said rod bent to extend below and under the trip dog of the binder.

3. In a device as herein characterized, in combination, a grain binder, a brace rod thereon, said binder also including a deck and a trip dog, a hand lever extending obliquely across said deck, pivot means for said lever and carried by said brace rod, said

pivot means including a horizontally elongated eye in which the said hand lever may slide and rock pivotally, an auxiliary trip rod having an angularly disposed upper end engaging said lever, supporting guides for said trip rod, the lower end of said rod angularly disposed beneath the trip dog of the binder, and spring means engaging the trip rod for maintaining it normally in inactive position.

YOUNG STOKES ELLINGSWORTH.
